APPARATUS FOR BENDING ELONGATED METAL ARTICLES

David Bruce Nivison, Brough, England, assignor to Blackburn Aircraft Limited, Brough, England

Application July 18, 1941, Serial No. 403,024
In Great Britain July 19, 1940

4 Claims. (Cl. 153—32)

The present invention is mainly concerned with the production of bent tubes, but it is conceivable that the general nature of the bending operation may also be applicable to the bending of lengths which are not necessarily of complete tubular form. Thus, it is contemplated that lengths of semicircular or other curved profile, channel, angle, or other sections may be bent out of their original longitudinal plane without necessarily or materially disturbing the profile. For convenience in the ensuing description and in the claims it is proposed to use the term "tubes" in a sense to cover such members as have been indicated above.

The invention is especially concerned with means for bending which lend themselves to mass-production whilst at the same time producing a finished article which is in no way inferior, and at least as to surface finish is even superior, to a product achieved as a result of normal hand- or machine-bending processes.

It is also worthy of mention that by employment of the process and means afforded by the present invention it is a simple matter to produce at a single operation a complicated bent formation which could be produced only with the greatest difficulty by hand or by the machines at present employed.

In certain of its applications the invention involves the operation of constraining the tubes to slide with respect to a shaping die which is formed of gradually increasing curvature defining ultimately the formation required to be imparted to the tube. Thus, where it is required to produce a complicated formation involving differently curved portions, or a very sharply curved portion, the shaping die may start with a straight portion or with a portion of a curvature of comparatively large radius, the curvature gradually increasing until at its finishing end the die defines the curvature ultimately required. By such means it is possible, by constraining the tube to slide in contact with the surface of the shaping die, to impart to it gradually-increasing curvature or a more complicated varying curvature than the tube would be able to withstand at a single stamping or die-pressing operation.

The invention may further be said to consist in means for bending tubes, which means comprise a shaping die of formation varying in curvature eventually to define the ultimate formation to be imparted to the tube, and means for sliding the tube in contact with the surface of the die to ensure eventually the desired curvature.

The nature of the die or dies may be such,

where certain ultimate formations are required, that only the curves or bends are actually defined by the dies so that intervening portions which are required to remain straight need not be engaged in a bending operation, which procedure may very considerably simplify die production and reduce expense, especially where the members to be bent have bends only, for instance, at one or both ends and/or at one or more spaced intermediate points.

Where a tube is likely to be subjected in the bending operation to such pressure that it is likely to crinkle at a bend, or even collapse, the tube may be filled with some suitable medium which will prevent collapse but will not materially interfere with the bending operation.

Where the tubes are internally loaded the filling medium may be liquid or solid, or even some granulated or powdered medium which is able to afford the required resistance to collapse. If a solid medium is employed, it is convenient to follow the usual procedure adopted by copper-smiths in pipe-bending operations according to which a closely-wound coil spring is first threaded through the tube, or positioned in the section, and is removed after the bending operation is completed. In many cases, however, it is preferred to use a solid and readily-bendable substance which may be used over and over again, and preferably one which can be heated to assume a liquid state. If the last-mentioned course be adopted, tubes cut to size ready for bending may be fed through a bath of the heated liquid on a conveyor belt so that they become filled with liquid which, on the tubes passing out of the tank, sets solid. After the bending operation has been completed, the tubes may be returned to the same tank, or may be otherwise heated until the filling medium returns to its liquid form, whereafter it can be emptied from or shaken out of the tube.

It is conceivable in some cases that any filling medium may advantageously be left in the tube to increase its ultimate strength.

The invention also includes varying the cross-section of a bent tube subsequent to and preferably in the same apparatus which performs the bending operation. Thus, for instance where it would not be practical to bend a tube which is required ultimately to have a somewhat oval or streamline cross-section, the shaping operation may be performed between dies which are not loaded highly enough to distort the cross-section during the bending operation, but which on being fully engaged at the end of the bending operation can, if necessary with the application of increased

pressure, press the bent tube so that it assumes the cross-section ultimately required.

In all cases it is preferred that the shaping die or dies should gradually and progressively increase in curvature until the ultimate formation required is defined. Such an arrangement is desirable so as to avoid subjection of the tube to any excessive loading. In some cases where any particular bend required might impose a high loading, or might stress unevenly in relation to the rest of the tube any particular section, it may be desirable to perform the bending operation in one or more stages, perhaps giving the tube an initial curvature which may even be different from that ultimately required before subjection to the final bending operation.

It is important to bear in mind that the bending operation may be in three dimensions. Thus, there may be bends up or down out of a horizontal plane, or laterally on each side of a vertical plane, while any particular curve may include a bend with a longitudinal direction component.

In some cases the tubes may be subjected to heat-treatment during a bending operation, for which purpose the dies may be heated.

To facilitate sliding of the tubes with respect to the shaping die or dies, they are preferably greased before being subjected to bending, and it may be mentioned that in many cases lead or zinc-faced dies, or dies formed of or faced with alloys including those metals, possess inherent lubricating properties which materially assist in carrying the invention into effect.

In order that it may be clearly understood and readily carried into effect, the invention is hereinafter described with reference to the accompanying diagrammatic drawing, of which:

Figures 1, 2 and 3 taken together represent an exploded perspective view of a pressure member, guide box and shaping die for producing a relatively complicated pipe bend, as seen for instance in Figure 3.

Figures 4 and 5 are sections taken longitudinally of the assembled guide box and shaping die showing the relationship of the associated members for varying positions of entry of the pressure member;

Figure 6 is a section taken on the line VI—VI of Figure 4.

Referring now to the embodiment of the invention shown in the drawing, which illustrates a typical arrangement for producing a fairly complicated bent tube, which is seen in the finished form at 22B in Figure 3, the stationary die is composed virtually of two separate parts, viz., the shaping die shown in Figure 3 and the guide box shown in Figure 2. In the particular embodiment now under review the part shown in Figure 1 can be more aptly regarded as a pressure member rather than a movable die member.

The shaping die itself is composed of the various sections 45 mounted in spaced relationship on the base board 46, which also mounts the back 47 which supports the curved sections 45 at their rear edges. It will be noticed that the straight tube 22B shown in broken lines in Figure 3 is engaging the leading ends of the curved sections 45, the curvature of which increases gradually until the sections 45 collectively define the curvature required when the tube 22B has been constrained to slide over the increasingly-curved surfaces of the sections 45 until it is bearing upon the base board 46. The guide

box shown in Figure 2 is positioned over the shaping die shown in Figure 3, the assembled condition of those members being shown more clearly in Figure 6. The guide box has a top plate 48 and a skeleton front frame 49, which mount spaced sections 50 complementary and opposite to the spaced sections 45. The arrangement is such that the spaced sections define a path of movement for the tube 22B to move down under pressure applied to the tube by means of the pressure member shown in Figure 1. The path of movement for the tube is indicated by the reference numeral 51 in Figure 6 and is the part actually occupied by the tube shown in the sections of Figures 4 and 5. At its lower end the path 51 finishes at the base board 46, and at its upper end terminates in an opening provided by virtue of the fact that the rear upper edges of the sections 50 are spaced from the back 47 of the shaping die.

It is particularly important to notice with respect to Figure 3 that towards the righthand end the tube 22B is given an upward sweep by engagement with the inclined face 51 of the fixed block 52. Again, the lefthand end section 45 develops a reentrant face, seen at 45', with which the curved edge, shown in dotted lines at 50' in Figure 2, cooperates in spaced relationship for maintaining the tube contiguous with the surface 45'. Furthermore, the lefthand end of the tube 22B is given a sweep somewhat rearwardly in relation to the back 47 due to the fact that it is constrained to slide down in contact with the cut-away surface 47.

It is obvious that practically any formation may be given to the tube 22B by forming the sections 49 and 50 appropriately. Likewise, if instead of the upward sweep being required at an end of the tube an upward bend were required at some intermediate point, a surface operating with similar effect to that represented at 51 would be provided at the intermediate point. Conversely, if instead of an upward bend the tube required at some intermediate point a downward bend, the base board 46 would be appropriately recessed for entry of the registering section of the tube into the recess under the influence of the pressure member.

Referring now to the pressure member, which is shown by itself in Figure 1, the sections 53 are adapted to interdigitate with the curved sections 45 of the shaping die and the constraining die members 50 of the guide box and to engage the tube and press it down the path 51 defined between the shaping die sections 45 and the constraining die members 50 of the guide box. The curved pressure section 54 is shaped so as to maintain engagement with the tube when it is running down over the reentrant surface 45'. Conveniently, the curved section 54 extends between the adjacent straight sections 53 at the lefthand end of the assembly, the sections 53 being securely attached to the undersurface of the top plate 55.

The shaping die shown in Figure 3 and the guide box shown in Figure 2 are positioned in their operative relationship by the locating battens 56 and 57.

In operation, the shaping die and guide box are assembled as shown in Figure 6. The tube 22B is then entered through the side of the assembly to assume the position in which it is shown in broken lines in Figure 3 and in Figure 6. The assembly of the shaping die and guide box and the insertion of the tube can easily be

effected while the shaping die is positioned on the bed of a press; the pressure member shown in Figure 1 is then inserted through the openings 58 which are cut in the top plate 48 of the constraining die to receive the sections 53 and 54 of the pressure member. The pressure member is lowered as a whole until the lower ends of its sections rest upon the tube which is itself resting on the top of the shaping die sections 45. The ram of the press is then operated, and consequently the tube 22B is forced from its chain-line position shown in Figure 3 to move down in contact with the increasingly-curved surfaces of the sections 45 until it acquires the desired formation, when the pressure member is fully engaged in the shaping die and guide box assembly. The pressure member can then be withdrawn and the guide box and shaping die are separated for removal of the finished tube 22B.

In case it should be thought that the procedure of preparing a shaping die, guide box and pressure member for each peculiar tube-bending operation is a tedious and cumbersome one, it is particularly important to bear in mind that the invention is in this case particularly concerned with the mass-production of bent tubes. Thus, it follows that once the dies have been produced each individual bent tube section can be shaped to its required formation in literally a matter of seconds; whereas a coppersmith working on a complicated bend might well take an hour in bending and fitting up his individual sections by the usual method employed in coppersmith's art. The invention is of particular importance where large numbers of standardized bent tube sections are required for the hydraulic control systems of aircraft, fuel feed lines, et cetera, in mass-production quantities. When once the bends required have been determined it is relatively a simple matter to produce the dies.

In some cases, particularly where the bends are complicated, the dies may impart to the tubes bends somewhat sharper than that actually required when the tube is removed from the die. Such provision may be necessary in some cases when operating with tubes which are formed of particularly springy material, the additionally severe curvature being in that case specially chosen to ensure the proper formation of the tube when the constraining influence of the dies is relieved.

In a case where a tube has an end bent back upon itself as a plain bend through 180°, it is to be understood that, though it is possible to effect such a bending operation by the provision of a suitable die at one and the same operation as that employed to bend the tube intermediate its ends, it may in many cases be simpler first to bend or curve the end back upon itself before subjecting the intermediate part of the tube to the bending operation in accordance with the invention.

In applying the pressure to the dies or equivalent shaping means, any pressing machine may be employed, and if it is required to bend a fairly long tube only at spaced points, it is contemplated that the tube may be located in guides which may have open or separable portions so that portable ram and shaping means may be used at the several points.

What I claim is:

- 10 1. Apparatus for bending tubes to a required formation comprising a plurality of spaced means collectively defining a stationary guideway of gradually increasing curvature, eventually defining the formation required, said guideway being of a uniform width not substantially greater than the external diameter of the tube to be bent, and a plurality of spaced means for displacing a tube laterally through said guideway to impart the eventually defined formation of the latter thereto, said spaced displacing means moving as a unit in interdigitating relationship through said spaced means defining a guideway.
- 15 2. Apparatus for bending tubes to a desired formation comprising cooperating means defining a stationary guideway of gradually increasing curvature eventually defining a desired contour in one plane, said guideway being of substantially uniform width not substantially greater than the external diameter of the tube to be bent, means for displacing a tube laterally through said guideway to impart the desired formation to the tube in said one plane, and means adjacent said guideway and in alignment therewith to effect deformation of the tube in a different plane.
- 20 3. Apparatus for bending tubes to a desired formation comprising a plurality of spaced means collectively defining a stationary guideway of gradually increasing curvature eventually defining a desired contour in one plane, said guideway being of substantially uniform width not substantially greater than the external diameter of the tube to be bent, means adjacent said guideway and in alignment therewith to effect deformation of the tube in a different plane, and a plurality of spaced means for displacing a tube laterally through said guideway to impart the desired formation to the tube, said spaced displacing means moving as a unit in interdigitating relationship through said spaced means defining a guideway.
- 25 4. Apparatus for bending tubes to a required formation which comprises means defining a contour of the desired tube formation, pressure means for gradually deforming a tube and shaping it to said contour, means restraining said pressure means to move in a plane normal to the plane in which the tube is bent, and means for moving said tube in a direction having components both normal to and parallel to the direction of movement of the pressure means, to cause the tube to be deformed to the desired contour.

DAVID BRUCE NIVISON.
